UNITED STATES PATENT OFFICE.

JOHN H. HANLON, OF SOMERVILLE, AND WILLIAM J. HANLON, OF FITCHBURG,
MASSACHUSETTS, ASSIGNEES TO HANLON LOCOMOTIVE SANDERS COMPANY,
OF WINCHESTER, MASSACHUSETTS, A CORPORATION OF MASSACHUSETTS.

TRACK-SANDER.

1,286,302.

Specification of Letters Patent.

Patented Dec. 3, 1918.

Application filed March 16, 1918. Serial No. 222,807.

To all whom it may concern:

Be it known that we, JOHN H. HANLON, of Somerville, in the county of Middlesex, and WILLIAM J. HANLON, of Fitchburg, in the county of Worcester, both in the State of Massachusetts, citizens of the United States, residing at 86 Elm street, West Somerville, and 116 South street, Fitchburg, respectively, have invented a certain new and useful Improvement in Track-Sanders, of which the following is a specification, reference being had therein to the accompanying drawings.

The invention has for its object a track sander to be used particularly on locomotives. The sander embodying the invention is particularly intended for use on locomotives which are already equipped with inside sanders contained within the sand dome. At the present time sanders are required which can be applied to the exterior of sand boxes and are operated wholly from the exterior so that they may be cleaned and cared for without removing the sand from the sand box. The sander embodying the present invention affords a device which can be applied to the exterior of the sand dome of a locomotive equipped with an inside sander. When so equipped, all the advantages of the outside sander are obtained and no changes of any kind have to be made in the sand dome.

As is well understood by those skilled in the art, it is desirable that the sand be discharged either by gravity or by some fluid under pressure, commonly compressed air. The sander embodying the invention is so constructed that the sand may be discharged either by gravity or by compressed air, but a single discharge pipe is employed instead of two as has heretofore been customary, thereby effecting a considerable saving in the expense of installation without in any way interfering with the effectiveness of the device in practical operation. The sander is also so constructed that the sand discharged by air from the sander will not cut out the body, neither will the sand leak out when the device is not in operation.

The invention will be fully understood by reference to the following description taken in connection with the accompanying draw-

ings, and the novel features thereof will be pointed out and clearly defined in the claims at the close of this specification. 55

In the drawings, Figure 1 is a rear elevation of a sand box located on a locomotive boiler provided with a track sander embodying the invention.

Fig. 2 is an enlarged view, partly in section of a track sander embodying the invention.

Referring to the drawings, at A is shown the boiler of the locomotive having its front at the right of Fig. 2. B designates the sand box, and C one of the bosses of the usual form. At D is shown a sander body comprising a casting of suitable shape provided with a flange 11 secured by bolts 12, to the boss C. The body D is provided with two 70 sand inlet passages 13 and 14 respectively, the passage 13 being toward the front of the locomotive. A discharge port 15 is connected with the sand discharge pipe 16. At 25 is shown the air discharge nozzle. The front 75 inlet passage 13 is directly in line with the sand discharge pipe 16 and registers with the passage 17 through the boss C of the sand dome, this being the passage through which sand was discharged by gravity when 80 the discharge of sand was controlled by the inside sander. The rear sand passage 14 registers with the passage 18 in the boss, this being the passage through which the sand

was drawn for discharge by compressed air 85 when the device was operated in connection with the inside sander. The rear passage 14 in the body is connected with the discharge passage 15 by a slightly inclined passage 30, which leads forwardly and slightly downwardly. It will be understood that the body of the sander lies on the slope of the boiler adjacent the bottom of the sand dome and therefore the downward slope of the passage 30 is in reality much less than appears in 95 Fig. 2. This arrangement prevents leakage of sand but permits the sand to be impelled by air toward the discharge opening without being obliged to take a circuitous path which inevitably results in rapid cutting of 100 the walls. At 20 is shown a plug which closes an opening 21 in the body D, said opening 21 being in line with the air nozzle 25 and arranged to permit the accumu-

lation of sand to form a sand cushion as described in my prior Patent No. 841,144 dated Jan. 15, 1907, which prevents the casting from being cut out by the stream of sand which moves at a high velocity.

At 22 is shown the air inlet pipe which communicates with an air chamber 23. In the wall 24 between the air chamber 23 and the interior of the sander body, is located 10 the air discharge nozzle 25 having passages 26 and 27 therethrough. The rear face of the nozzle is slotted as shown at 28 so that it may be turned by a screw driver when it is desired to remove it. A clean out plug is 15 provided at 29 by means of which the opening into the air chamber 23 is opened to permit the removal of the air discharge nozzle 25 or to permit the chamber 23 to be blown out. By this construction it is never 20 necessary to remove the air nozzle to clean it. This is a great advantage because if the nozzle is removed the sand will at once flow into the opening from which the nozzle was removed and will make the restoration of 25 the nozzle nearly impossible unless the sand box is emptied of sand and the interior of the sander cleaned.

At 19 is shown a clean out plug located directly below the inlet opening 14. By re- 30 moving this plug any accumulation of stones, roots or the like may be easily removed.

In the operation of the sander, sand is discharged by gravity through the passage 13 directly into the said discharge pipe 16, 35 the flow of sand being controlled by the sand valve located in the sand box and not shown in the drawings. When the sand is discharged by air pressure as is the ordinary method, it enters from the sand body 40 through the passages 18 and 14 and is then impelled by compressed air from the nozzle 25 on a substantially horizontal line in the general direction of the plug 20. Thence it escapes through the discharge pipe 16 to 45 the rails.

What we claim is:

1. In combination with a sand box having a boss through which are two passages one for the discharge of sand by gravity and the 50 other for discharge of sand by compressed air, a body secured to said boss and having

two passages registering with the two passages in the said boss, a common discharge opening in the body, a transverse passage connecting with the said common discharge opening, said common discharge opening being directly in line with the gravity discharge opening in the boss, and an air discharge nozzle located near the junction of the connecting air passage and the air inlet sand passage, the discharge end of the transverse passage being at least as low as the air discharge nozzle.

2. In combination with a sand box having a boss through which are two passages one 65 in front of the other, the forward passage being for the discharge of sand by gravity, and the other being for the discharge of sand by compressed air, a body secured to said boss and having two passages registering with the two passages of the boss and uniting in a common discharge opening arranged directly in line with the forward passage in the said boss there being in the said body a passage inclined downwardly 70 slightly connecting the rear inlet passage with the front inlet passage and an air nozzle located near the junction of said inclined passage with the rear inlet passage.

3. In combination with a sand box having 80 a boss through which are two passages one for the discharge of sand by gravity and the other for the discharge of sand by compressed air, a body secured to said boss and having two passages registering with the 85 two passages in the said boss, the passage in the body which connects with the air sand discharge passage in the boss sloping away from the gravity passage in the body, a transverse passage which slopes slightly 90 downwardly connecting the two passages in said body, there being a common discharge opening directly in line with the gravity discharge opening in the boss, and an air discharge nozzle located above the junction of 95 the transverse passage and the discharge pipe.

In testimony whereof we affix our signatures.

JOHN H. HANLON.
WILLIAM J. HANLON.
